WILLIAM B. NELSON.

By His Attorney

W. Anthony Neira

UNITED STATES PATENT OFFICE.

WILLIAM B. NELSON, OF FAIRFIELD, ALABAMA.

METHOD AND APPARATUS FOR REMOVING SCALE.

Application filed August 7, 1926. Serial No. 127,843.

- This invention relates to an improved method and means for rolling iron and steel and is particularly directed to the idea of reducing the amount of roll scale which adheres to shapes during the process of rolling the same. The invention will be apparent from the following specification when read in connection with the accompanying drawings in which—
- 10 Fig. 1 is a side elevation of part of a rolling mill embodying certain features of the invention;
- Fig. 2 is an end view of a portion of Fig. 1;
- 15 Fig. 3 is a transverse section of a billet illustrating the step in method of rolling;
- Fig. 4 is a side elevation showing several roll stands and illustrating my method diagrammatically.
- 20 Referring in detail to the drawings, 10, 12 and 14 represent stands of a rolling mill, the rolls 16, 18 and 20 of which are so shaped that the billet B is rolled to a concave cross-section as indicated in Fig. 3.
- 25 During the rolling operation I supply a water or other cooling medium to the billet by convenient means, as for instance, through pipes 22 with suitable control valves 24 therein. The water fills the concave portion of the billet for a considerable length, for example, practically that length determined by the spacing of the rolls 10 and 14. It is especially advantageous to fill the concave section full of water so that the same
- 30 may contact with the billet throughout a great length so as to efficiently cool the roll scale. Adjacent to the rolls 20 of the stand 14, I provide a pair of rolls 26 and 28 adapted to bend or straighten the billet so as to loosen or break off the chilled roll scale. Fig. 2 shows the billet B thus straightened. After passing through the rolls 26 and 28, the loosened or broken scale is blown off by means of air or other fluid, discharged from
- 35 a pipe 30. The shape or billet then passes to the rolls 32 of the stand 34 and to rolls 36 or stand 38 where it is further reduced in cross-section or finished or leaves these rolls in a flat shape, or any shape desired.
- 40 The bending rolls 26 and 28 shown in Fig. 4 are idlers and the billet is drawn through them by power from the rolls in the
- stand 34. Where the shape being rolled does not subsequently pass through finishing rolls, it is understood that the bending rolls 55 may be power driven. Bending rolls may be placed on any roll stand, or all roll stands, for purposes stated herein.
- While the billet shown is of substantially rectangular cross-section, it is to be understood that various other shapes may be formed according to my improved method and the term concaved used in the claims is intended to cover the billets having various configurations, the idea being that the billet 60 will hold water for a considerable portion of its length so as to thoroughly chill the roll scale.
- Various modifications may be made by those skilled in the art without departing 65 from the invention as defined in the appended claims.
- What I claim is:—
1. In the rolling of metal the method which consists in maintaining the billet concaved for a suitable length and holding a body of water therein, subsequently bending the billet to crack off the chilled scale and blowing off the scale by fluid pressure. 70
2. In the rolling of metal the method which consists in concaving the billet, holding a cooling medium in contact with it throughout a considerable length thereof to chill the roll scale and protect the billet from oxidation, bending the billet to loosen 75 the scale and blowing off the scale.
3. An apparatus of the class described comprising rolls shaped to bend the billet transversely to a convex cross-section, means for feeding a cooling medium to the billet, 80 rolls for bending the billet to loosen the roll scale and means for blowing off the loosened scale. 85
4. An apparatus of the class described comprising rolls shaped to bend the billet transversely to a convex cross-section, means for feeding a cooling medium to the billet, 90 rolls for bending the billet to loosen the roll scale and means for removing the scale thus loosened. 95
- 100 In witness whereof, I have hereunto signed my name.

WILLIAM B. NELSON.
